UNITED STATES PATENT OFFICE.

BENJAMIN S. PORTER AND CLARENCE W. PORTER, OF RED OAK, IOWA, AS
SIGNORS OF ONE-HALF TO N. A. KEYS AND F. H. KEYS, BOTH OF SAME
PLACE.

ROAD-CART.

SPECIFICATION forming part of Letters Patent No. 374,625, dated December 13, 1887.

Application filed May 14, 1887. Serial No. 238,230. (No model.)

To all whom it may concern:

Be it known that we, BENJAMIN S. PORTER and CLARENCE W. PORTER, citizens of the United States, and residents at Red Oak, in the county of Montgomery and State of Iowa, have invented certain new and useful Improvements in Road-Carts; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a bottom view of our invention. Fig. 2 is a vertical longitudinal section, and Fig. 3 is a detail view.

This invention has relation to two-wheel vehicles; and it consists in the construction and novel combination of parts, as hereinafter set forth.

In the accompanying drawings, the letter A designates the shaft-bars, and B the seat-bars or seat-frame connected thereto in front of the seat.

C is the axle, and D a transverse bar connecting the shafts.

E E are chord-braces and torsion-springs combined. Each of these springs consists of the main torsional portion F, the front securing-offset, G, extending inward and fastened to the shaft-frame, and the rear arm, H, also extending inward.

K represents a clip-bearing connected to the axle and receiving the rear end of the torsional portion F of the spring. A downward extension or arm, L, of the seat-frame on each side is connected to the inner end of the arm H of the spring. These chord-springs brace the curved rear portions of the shaft-bars, and at the same time form strong torsional springs for the seat.

Having described this invention, what we claim, and desire to secure by Letters Patent, is—

1. The combination, with the shafts and seat-frame, of chord-braces, serving, also, as torsion-springs for the seat-frame, substantially as specified.
2. The combination, with the shafts and seat-frame having downward extensions or arms, of the chord-brace torsion-springs E E, connected by clip-bearings to the axle, secured by front offsets to the shaft-frame, and having inwardly-extending arms connected to the downward extensions of the seat, substantially as specified.

In testimony whereof we affix our signatures in presence of two witnesses.

BENJAMIN S. PORTER.
CLARENCE W. PORTER.
